UNITED STATES PATENT OFFICE.

ERNST R. GUSTAVUS, OF OSHKOSH, WISCONSIN.

STEAM-BOILER.

No. 841,513.

Specification of Letters Patent.

Patented Jan. 15, 1907.

Application filed June 30, 1906. Serial No. 324,270.

To all whom it may concern:

Be it known that I, ERNST R. GUSTAVUS, a citizen of the United States, residing at the city of Oshkosh, in the county of Winnebago and State of Wisconsin, have invented new and useful Improvements in Steam-Boilers, of which the following is a specification.

My invention relates to internal furnace-boilers.

10 My invention consists in a sectionally-constructed internal tubular furnace comprising in its construction a series of tubes having outwardly-turned circumferential flanges, said flanges being joined by rivets, thus providing means for expansion and also stiffening rings or ribs at each sectional junction.

20 My invention further consists of a sectionally-constructed furnace comprising in its construction a series of tubes having outwardly-turned circumferential flanges, means for joining said flanges together, the front section being so constructed as to gradually diverge circumferentially toward the front, 25 but upon the same line of base as the other sections.

30 My invention further consists of a tubular boiler having a front and rear head, one or more circular openings in the front head and one or more corresponding circular openings 35 in the rear head beneath the boiler-flues, the front openings being larger than their respective rear openings, inwardly-extending angular flanges around said openings in both heads, and means for joining the interior furnace to said flanges.

40 In the accompanying drawings a double furnace is shown adapted to large tubular boilers.

45 Figure 1 represents a vertical section longitudinally of the boiler and one of the furnaces. Fig. 2 represents a front view with one-half portion of the boiler-front removed.

Referring to the drawings by numerals, 2 represents the boiler-front.

3 represents the furnace fire-doors.

4 represents the breeching, and 5 represents the stack.

6 represents the ordinary flue-door.

50 7 represents the front head of the boiler, and 8 represents the rear head.

9 9, &c., represent the flues.

10 10, &c., represent stay-rods.

11 represents the rear combustion-cham-

ber, which is preferably constructed of brick 55 with a fire-brick roof.

12 represents the grates, and 13 represents the fire-arch.

14 represents the furnace-opening in the front head, and 15 represents the furnace-opening in the rear head. The furnace-opening in the front head is larger than the furnace-opening in the rear head. Circumferentially of said openings there is provided inwardly-extending angular flanges 16 and 16' front and rear.

It will be observed that in my invention the furnace is hung or suspended within the boiler and attached, by means of rivets 17 17 17, &c., to the flanges 16 and 16'. 70

In my invention the tubular furnace is constructed in sections 18 18 18, &c., each section being provided with outwardly-turned flanges, and these flanges being riveted together at 19 19 19, &c. The flanges 75 when so riveted for ribs or rings to afford means of expansion and to further afford stiffening-ribs for the support of the furnace. The front section 20 is constructed gradually diverging circumferentially toward the front, 80 but with the same base as the general line of base of the furnace.

The fire-front 21 is bolted to the boiler-head by a series of bolts 22 22 22, &c.

By means of my invention, the construction of the furnace and the front boiler-head opening being larger than the rear opening, I am able by removing the fire-front 22 and then knocking out the confining-rivets 17 17 17, &c., to withdraw the entire furnace 90 through the front opening in the boiler-head. I regard this as an essential feature of my invention, because it is often necessary to repair the furnace, and by withdrawing the same I afford a means of easily perfecting the 95 repairs.

In my invention it will be observed that none of the boiler-flues are below the furnace, and all are located practically above the furnace. In the operation of the furnace the 100 bed or floor is relatively cold in comparison with the top of the furnace. Means must therefore be afforded to permit expansion and contraction or else the furnace-jacket will warp. By means of my segmental or 105 sectional construction, as described, I afford a series of joints which accommodate to the expansion and contraction of the furnace

and further afford a series of ribs or rings to stiffen the furnace. By means of the upwardly-inclined top surface 20 the outward pressure of the steam toward the boiler-front 5 is broken against the incline.

It will be observed that the roof of the expansion-chamber is limited in height to the height of the tubes within the boiler. In expansion-chambers heretofore constructed 10 of this class the roof of the chamber has been allowed to join the boiler at the top line of the boiler. In such a construction the excessive heat from the furnace radiating against the upper portion of the boiler, 15 which is practically unbalanced, has caused a burning out of that portion and of the anchorages to the tie-rods 10 10, &c., or other brace-rods that may be used.

Having thus described my invention, what 20 I claim, and desire to secure by Letters Patent, is—

1. In a steam-boiler, an internal tubular furnace comprising in its construction sectional tubes having outwardly-turned circumferential flanges and means for joining 25

said flanges, the front section being so constructed as to gradually diverge circumferentially toward the front, said section being upon the same line of base as the other sections, substantially as shown. 30

2. In a steam-boiler, an internal tubular furnace comprising in its construction sectional tubes having outwardly-turned circumferential flanges and means for joining said flanges, the front section being so constructed as to gradually diverge circumferentially toward the front, said section being upon the same line of base as the other section, said furnace being suspended from inwardly-turned flanges around front and rear 35 40 openings in the boiler-heads, and removable means for attaching said furnace to said flanges, substantially as shown.

In testimony whereof I affix my signature in presence of two subscribing witnesses.

ERNST R. GUSTAVUS.
